(57) **CLAIM**

The ornamental design for a bracket, as shown and described.

DESCRIPTION

This application recognizes the following applications:

U.S. Design patent application Ser. No. 29/420,756, filed May 11, 2012, now U.S. Design Pat. No. D746122; U.S. Design patent application Ser. No. 29/614,843, filed Aug. 23, 2017, now U.S. Design Pat. No. D892597; and U.S. Design patent application Ser. No. 29/770,973, filed Feb. 18, 2021, the disclosures of which are hereby incorporated by reference in their entireties.

FIG. 1 is a perspective view of a bracket of the present invention.

FIG. 2 is a front elevation view thereof.

FIG. 3 is a rear elevation view thereof.

FIG. 4 is a left side elevation view thereof.

FIG. 5 is a right side elevation view thereof.
